APPARATUS FOR LOCATING SHOES AND SOLES FOR CEMENT ATTACHMENT

Sidney J. Finn, Beverly, Mass., assignor to United Shoe Machinery Corporation, Borough of Flemington, N. J., a corporation of New Jersey

Application July 26, 1939, Serial No. 286,600

49 Claims. (Cl. 12—33)

This invention relates to apparatus for use in the cement attachment of soles to shoes and particularly for use in relatively locating the shoe and sole prior to the application of sole-attaching pressure.

The invention is illustrated as embodied in a cement sole attaching machine of the type disclosed in United States Letters Patent No. 2,047,185, granted July 14, 1936, upon application of Ballard et al.

Objects of the invention are generally to improve and perfect mechanism for relatively locating the shoe and sole and particularly to enable the shoe and sole to be located relatively to each other prior to their being brought into contact, and to insure that the length of the shank portion of a sole will correspond substantially to the length of the shank portion of the shoe against which it is laid.

The invention consists in means for locating the sole relatively to a pad upon which the shoe is to be pressed and means for frictionally holding the shoe in the proper position above the sole out of contact therewith, the shoe and sole being brought together by application of sole-attaching pressure. As illustrated, a sole is located and the shoe is suspended in proper position relatively to the located sole between a V-gage at the toe end of the shoe and a V-gage at the rear end of the shoe, one V-gage being fixed and the other yieldingly pressed toward it to sustain the shoe.

The method aspect of the invention herein disclosed but not claimed is made the subject-matter of a divisional application Serial No. 356,918, filed September 16, 1940, in my name.

Other features of the invention consist in shoe and sole gages located at the ends of the ball line and cooperating with the gages at the end of the toe relatively to locate the forepart of the shoe and sole with means permitting bodily lateral movement of the rear shoe and sole gages to enable them relatively to locate the shoe and sole in the positions determined by the toe and ball line gages.

To accommodate the gages for right and left shoes and to the different swings of lasts for the same foot, the sole and shoe toe gages are arranged for adjustment laterally of the shoe with respect to the ball gages and, as illustrated, are arranged to move about a center located in the vicinity of the intersection of the longitudinal median line of the forepart with the longitudinal median line of the rear part of the shoe bottom.

These and other features of the invention, in-

cluding certain novel arrangements and combinations of parts, will appear more fully from the following description when read in connection with the accompanying drawings and will be pointed out in the appended claims.

In the drawings,

Fig. 1 is a plan view of a pad box equipped with shoe and sole locating mechanism embodying the present invention;

10 Fig. 2 is a detail in plan of one of the ball line gages shown in Fig. 1 in its open position;

Fig. 3 is a longitudinal section on the line III—III of Fig. 1, the parts beyond that line being shown in elevation;

15 Fig. 4 is a sectional view on the line IV—IV of Fig. 3 and showing the toe gage locking mechanism;

Fig. 5 is a detail in front elevation of the parts shown in Fig. 3;

20 Fig. 6 is a view taken on the line VI—VI of Fig. 1 showing in elevation the mechanism for operating the ball line gages;

Fig. 7 is a perspective view of the gage for locating the toe end of the sole; part of the associated gage for the toe of the shoe being broken away;

Fig. 8 is a side elevation of the mechanism for locating the rear ends of the sole and shoe;

Fig. 9 is a central vertical section of the mechanism shown in Fig. 8;

30 Fig. 10 is a transverse section taken on the line X—X of Fig. 8 looking toward the toe;

Fig. 11 is an elevational detail of parts shown in Fig. 10; and

35 Fig. 12 is a somewhat diagrammatic view illustrating the location of a shoe and sole in accordance with the present method.

In Fig. 1 a shoe S and an outsole O are shown as relatively located by mechanism embodying the present invention as applied to a machine of the type disclosed in the patent referred to above, the pad being of the type disclosed in Letters Patent of the United States No. 2,205,400, granted June 25, 1940, on my application. The mechanism for locating the toe end of the sole, best shown in Figs. 1, 3 and 7, comprises a forked member 20 (Fig. 7) each arm of which has a pair of downwardly projecting ears 22 to which a pair of plates 24, 26 are pivoted by a pin 28 so that the free edges of the plates may rest by gravity against a cover 30 overlying a pad 31 contained in a box 32. The free edges of the plates 24, 26 are straight and flush with each other and the free edges of one pair of plates 24, 26 are angularly related to the free edges of the other pair of plates so that the plates constitute a V-

gage which will locate the toe end of a sole when brought against it. As shown, the sides of the V are substantially at right angles to each other. The forked member 20 is carried by a slide 34 arranged for movement longitudinally of the sole in the direction of the longitudinal median line of the forepart, and the gage-carrying end of the slide 34 is arranged for a limited amount of movement perpendicularly to the pad cover 30 about a pivot stud 36. In order that the free edges of the plates 24, 26, while resting upon the cover 30, may have at all times a limited amount of upward movement in response to the distortion of the pad, the slide 34 is provided with a downward projection 35 which rests upon the pad cover 30 adjacent to the plates 24, 26 and limits downward movement of the front end of the slide 34 and prevents contact of the plates 24, 26 with an overlying shoe gage to be later described.

The slide 34 is arranged for up-and-down swinging movement about the pivot stud 36 and for longitudinal movement toward and from the shoe between ways 38, 39 formed in a member 40, as best shown in Fig. 4 where the pivot stud 36 is shown as having a square head 41 arranged to slide in the way 38, the other end of the stud 36 carrying a square washer 45 which slides in the way 39. The member 40 has on its under side (Fig. 3) a T-shaped guideway 43 to receive a curved plate 44 supported at its ends on two brackets 46 (Fig. 1) extending outwardly from opposite corners of the front end of the pad box 32. The plate 44 is curved about a center located approximately at the intersection of the longitudinal median line of the forepart with the longitudinal median line of the rear part of a sole disposed upon the pad cover 30. The member 40 may be adjusted along the curved plate 44 to locate the sole V-gage 24, 26 properly for right and left soles or for soles having different swings by releasing a set screw 48 (Fig. 1) and sliding the member 40 along the curved plate 44 to the required position where it is maintained by tightening the screw.

After a sole is placed by the operator on the pad cover 30 in approximately the right position, it is desirable to move the sole V-gage in the direction of the longitudinal median line of the forepart to engage the toe end of the sole and to lock it in that position. For this purpose mechanism shown in Figs. 1, 3, 4 and 5 is provided.

The slide 34 (Fig. 3) has pivoted thereto by the stud 36 a lever 52 on which is a cam 54 the surface of which, when the lever 52 is turned in a clockwise direction, engages a wear plate 56 secured to the upper wall of the way 39 on which the washer 45 slides. The lever 52 is urged in a counterclockwise direction by a compression spring 58 having one end seated in the lever and the other in the slide 34, the spring being adjustable by means of a screw 60 and set nut. A link 62 is connected to the lever 52 at 64 and to the upper arm 66 of a lever having a lower arm 68, the lever being pivoted at 70 between a pair of spaced brackets 72 extending downwardly from the member 40. Pivoted on the same axis 70 with the lever 66, 68 is a lever having an upper arm 74 and a lower arm 76, the upper arm 74 being bored out to receive a compression spring 78 which is adjustably held in place by a screw 80. The lower end of the spring 78 engages a socket in the rearwardly extending arm 68. The relative movement between the lever arms 68 and 74 produced by the spring 78 is limited by a stop screw 84 threaded through the arm 66 and en-

gaging the arm 74. By adjusting the screw 84 the initial position of the shoe and sole V-gages lengthwise of the shoe may be varied. The arm 76 is bored to receive a stud 86 on which is a roll 88 lying in a groove 90 curved from the same center as the plate 44 but having a somewhat longer radius. The groove 90 is formed in a rocker member 92 (Fig. 1) pivoted at each end to one of the brackets 46 by a pin 94, the axes of the pins being substantially in alinement with the pivot 70 of the lever 66, 68. On the side of the pad away from the operator the rocker 92 has an upwardly extending arm 96 (Figs. 1 and 6) which is pivoted at 98 to a link 100 the other end of which is arranged to slide in a guide 102 (Fig. 1) and carries a roll 104 engaging a groove in the upper end of a bell-crank lever 106 similar to that provided in the machine of the Ballard et al. patent above referred to for operating the gages. A tension spring 108 (Fig. 1) connected between the link 100 and a pin 110 on the pad box serves to swing the rocker 92 in a clockwise direction yielding to move the shoe and sole locating mechanism toward the shoe when the lever 106 is released to permit action of the spring 108.

When the lever 106 is so released, the spring acts to turn the rocker 92 in a clockwise direction, thus swinging the lever 74, 76 about its pivot 70 and through the spring 78 turning the lever 66, 68 on the same pivot, the link 62 acting on the lever 52 through the spring 58 to move the slide 34 toward the sole. When the V-gage 24, 26 engages the sole and resistance is thus offered to its further movement, the spring 58 yields and the consequent clockwise movement of the lever 52 causes the cam 54 to engage the plate 56, thus effectively locking the slide 34 against movement in a direction away from the shoe, pressure in that direction merely serving to jam the surface of the cam 54 harder against the plate 56. The spring 78 may then yield to permit further movement of the rocker 92.

To locate the toe of the shoe with respect to the toe of the sole located in the V-gage 24, 26, a gage 112 is provided. The gage 112 has two faces 113 (Fig. 1) which are angularly related to each other, the angle as shown being approximately a right angle. The faces 113 have considerable heightwise extent in a direction perpendicular to the pad surface, the surfaces 113 being substantially parallel to the edge faces of the plates 24, 26. The gage 112 having the surfaces 113 is therefore a V-gage for locating the toe end of the shoe. The V-gage 112 is adjustably connected at 114 to a slide 116 (Fig. 3) arranged on the slide 34 for movement in a direction parallel thereto, the slide 116 being held in place on the slide 34 by a screw 118 passing through a slot in the slide 116 and threaded into the slide 34.

Since, in some shoes, more projection of the sole is required on one side than on the other, the shoe V-gage 112 is arranged for adjustment laterally of the shoe with respect to the sole V-gage 24, 26. For this purpose the slide 116 has a transverse groove 120 which is engaged by a downwardly projecting tongue on the V-gage 112, the gage being provided with a slot 122 (Fig. 1) extending in the direction of the groove 120 to receive the screw 114.

The slide 116 is moved longitudinally relatively to the slide 34 to adjust the shoe V-gage 112 relatively to the sole V-gage 24, 26 to vary the amount of extension of the sole by means of a screw 124, the head 126 of which engages a notch 128 formed

in the slide 34, the screw 124 being threaded through an upstanding lug 130 on the slide 116. Between the head 126 of the screw and the lug 130 is a compression spring 132 which prevents accidental turning of the screw.

To indicate the setting of the shoe gage 112 longitudinally of the shoe with respect to the sole gage 24, 26, indicating means best shown in Figs. 3 and 7 is provided. A plate 134 (Fig. 7) is provided with graduations 136 and has a supporting portion 138 attached by a screw 139 (Fig. 3) to the slide 34. An index finger 140 is pivoted at 142 to the plate 134 and a bifurcated arm 144 also pivoted at 142 is adjustably held to the finger 140 by a screw 146 which passes through a slot in the finger 140 and is threaded into the bifurcated arm 144. A stud 148 fixed to the slide 116 is embraced by the bifurcated arm 144 and the plate 134 is slotted at 150 to permit movement of the stud 148 relatively to the plate as the slide 116 is moved relatively to the slide 34 by turning the screw 124 which causes the finger 140 to move over the graduations 136 and indicate the position of the shoe V-gage 112 relatively to the sole gage 24, 26. By loosening the screw 146 the finger 140 may be made to coincide with any desired one of the graduations 136 for any given longitudinal setting of the surfaces 113 of the V-gage 112 with respect to the V-gage 24, 26. Thus any number of pad boxes may have their indicators 140 so set that they will be opposite the same number on the plate 134 when the gages 112 are set for the same sole projection on all the boxes.

After the sole V-gage 24, 26 is moved toward the toe end of the sole (accompanied, of course, by the shoe V-gage 112), ball line sole gages 152, 154 are moved toward the sole from opposite sides thereof to engage it substantially at the ends of the ball line. Each ball line gage has a stem 156 (Fig. 1) which is adjustably connected by a screw and slot at 158 to an arm 160 pivoted on a horizontal axis 162 (Fig. 6) to a member 164 which, in turn, is pivoted on an upright pin 166 carried by one of the brackets 46. Beneath each arm 160 is a plate 168 (Fig. 1) having an inclined slot 170, each plate being pivoted on one of the pins 166 and having a projection 172 riveted at 173 (Fig. 6) to a projection 174 on the member 164 so that the plate 168 and the arm 160 turn together on the pin 166. Each arm 160 is provided with a vertical pin 176 (Figs. 1 and 2) which extends downwardly into a slot formed in the plate 168, the pin fitting loosely in the slot to permit sufficient heightwise movements of the gages 152 so that they will at all times engage the pad and may move heightwise in response to distortion of the pad by reason of the pressure of the shoe upon it, the pins further insuring that the arms 160 will move inwardly with the plates 168 without any springing of the plates as the latter are moved inwardly by means to be described.

The slot 170 in each plate 168 is engaged by an upstanding lug 178 on a slide 180, each slide being mounted in ways 182 for movement lengthwise of the pad box, the ways 182 on one side of the box being parallel to the ways 182 on the other side of the box. Each slide 180 is connected by a link 184 (Fig. 6) to the upper arm 186 of a lever pivoted at 94 and having a lower arm 188 which lies in a widened end portion 189 of the groove 90, said arm being held yieldingly against the left-hand side of the groove by a plunger 190 backed up by a compression spring 192. Accordingly, when the rocker 92 is rocked

in a clockwise direction the plungers 190, one at each side of the box, press upon the arms 188 and yieldingly swing the arms 186 clockwise to move the slides 180 rearwardly of the shoe and cause the lugs 178 in the inclined slots 170 to move the gages 152, 154 toward the sole from opposite sides thereof. When one of the ball gages engages the sole, the spring plunger 190 through which that gage is operated will yield to permit further movement of the other gage into contact with the sole, the gages 152, 154 thus acting as feelers to find the sole on the pad without changing its location. The inclination of the slots 170 is such that both gages are positively locked against outward movement until released by reverse movement of the lugs 178.

Above the sole gage 152 is a shoe gage 194 arranged to slide laterally of the sole relatively to the sole gage 152, the gage 194 being adjusted toward and from the shoe by means of a screw 196 which is held from endwise movement relatively to the sole gage 152 and is threaded into the shoe gage 194. A similar shoe gage 198 is similarly mounted upon the other sole gage 154.

It is desirable that the sole V-gage 24, 26 be advanced to engage the toe end of the sole before the ball line gages 152, 154 are brought into engagement with the sole. Accordingly, a portion 171 of the inner side of the slot 170 against which the lugs 178 act to close the ball line gages, is made parallel to the ways 182 so that during the initial movement of the lugs no movement is imparted to the ball line gages, the sole V-gage 24, 26 having meanwhile been brought into engagement with the sole. Thereafter, of course, the lugs 178 move on to the inclined portion of the inner sides of the slots 170 and move the ball line gages into contact with the sole, as already described.

The mechanism for locating the rear end of the sole and shoe will now be described with reference to Figs. 8, 9, 10 and 11. At the rear end of the pad box is a vertical slide 200 sustained by springs, as is usual in this type of machine.

On the slide 200 is a transverse T-guide 202 on which a transverse slide 204 is mounted. Near the top of the slide 200 extending transversely of the pad box is a bore 206 (Fig. 10) extending part way through, and on the opposite side of the pad box is a similar bore 206. In each bore is a headed pin 208 on which is a compression spring 210. On the outer end of each pin, held on by a cotter pin 211, is an ear 212 through which the pin passes, each ear being secured to

the slide 204 by a screw 214. The springs serve to maintain the horizontal transverse slide 204 in central position with respect to the vertical slide 200 but permit the slide 204 to be displaced laterally with respect to the slide 200 in either direction by compressing one only of the springs 210. The slide 204 has a rearward extension 216 (Fig. 9) arranged to engage a roll 218 mounted on a rearward extension 220 of the slide 200, this extension insuring that the slide 200 will move easily without binding when subjected to rearward pressure by a shoe. Mounted in a T-way 222 on the slide 204 is a longitudinal slide 224 which carries both sole and shoe gages. The movement of the slide 224 is limited in both directions (Fig. 9) by stop screws 225, and to permit greater longitudinal movement of the slide 224 its under side is slotted at 227 to receive the stop screws 225, the screws engaging an unslotted portion of the slide between the grooves 227. The

front part of the slide 224 is hollow and mounted

in the cavity is a sole gage comprising a tongue 226 secured by screws 228 to a member 230 fixed to a transverse pin 232 which extends through and beyond the sides of the hollow portion of the slide 224. Rearwardly of the pin 232 the member 230 is engaged by a compression spring 234 which tends to force the forward end of the tongue 226 downwardly. The tongue 226 carries a pin 236 adapted to engage a hole punched centrally of the rear end of the sole, the pin, as shown, being beveled off on its rear side to facilitate its removal after the sole is attached to the shoe. The pivot of the pin 232 which extends beyond the slide 224 on the side toward the operator has pinned thereto a block 238 (Figs. 8 and 10) the upper part of which is slotted vertically to receive the lower end of a lever 240 which is pivoted thereto by a pin 242 and has below the pin flat surfaces 241, 243 which overlie the flat surface 244 of the block 238 (Fig. 8). When the lever 240 is moved clockwise, the surface 241 will, after some lost motion, engage the surface 244 and will then turn the pin 232 to cause the tongue to be raised against the tension of the spring 234.

A V-gage 248 to receive the rear end of the shoe has a longitudinally bored square stem 250 which is received between vertical surfaces 252 (Fig. 10) formed in the slide 224. The stem 250 is slotted at 254 (Fig. 9) to receive a transverse pin 256 the ends of which are fixed in the slide 224, and in the bore of the stem between the pin 256 and a cotter pin 258 is a compression spring 260 which tends to push the gage 248 yielding toward the shoe, the stem 250 being permitted a limited amount of movement in a vertical plane about the pin 256. The stem 250 is normally held in an upwardly tilted position against a stop 262 (Fig. 8) by a leaf spring 264 secured to the slide 224 by a screw 266 (Fig. 9) and bearing at its front end upon the lower side of the stem 250 forwardly of its pivot 256. The free end of the spring 264 lies in a shallow groove 251 formed in the lower face of the stem 250, and a pair of lugs 268 on the member 230 are engaged by the stem 250 at opposite sides of the groove 251 when the gage 248 is depressed and serve to limit downward movement of the gage.

To hold the slide 224 from rearward movement, a pair of pawls 270, 272 (Fig. 8) is provided, these pawls being pivoted at 274 to the slide 224 and arranged to engage ratchet teeth 276 formed in a steel strip 278 inserted in the top face of the slide 204 and held in place by screws 280. The pawls 270, 272 are differentially arranged, that is, arranged so that when one pawl engages the notch between the teeth 276 the other pawl will be at the top of another tooth. The pawl 272 has a tail 282 and the other pawl 270 has a similar tail 284. The tail 282 is connected by a tension spring 286 to a pin 288 on the slide 224, the spring holding the pawl 272 in engagement with the teeth 276. To insure that the pawl 270 will also be urged toward the teeth 276, a portion 290 of the pawl 272 is arranged to overhang the pawl 270, and a compression spring 292 is arranged between the portion 290 and the pawl 270, the spring being socketed in each of these members. The lever 240 is provided with a rearward projection 294 arranged to engage flat surfaces formed one on each of the tails 282, 284. When the lever 240 is operated to lift the tongue 226, lost motion

occurs between the surface 241 of the lever and the surface 244 on the block 238 sufficient to enable the projection 294 to engage and lift the pawls before the tongue 226 is released by further movement of the lever.

If, as sometimes may happen, the tongue 226 is tilted upwardly, due to pressure of the shoe upon the pad, the block 238 will swing rearwardly and the projection 294 will merely slide back and forth on the flat surfaces formed on the tails of the pawls without lifting the pawls, so that the slide 224 remains locked against rearward movement.

It is sometimes desirable to shift the shoe gage 248 and the tongue 226 laterally with respect to each other to meet conditions where the hole in the sole is improperly located or the shape of the last is unsymmetrical so that the location of the pin 236 centrally with respect to the shoe V-gage 248 does not locate the rear end of the sole properly with respect to the shoe bottom. For this purpose the pin 232 which extends beyond the slide 224 on the side away from the operator (Figs. 10 and 11) is provided with a pair of flanges 296 between which is located a collar 298 formed on a screw 300 threaded into the slide 224. By turning the screw 300 by its head 302 the pin 232 is moved longitudinally and hence the tongue 226 which is pinned to it will be moved laterally with respect to the shoe gage 248. A friction plug 303 prevents accidental turning of the screw 300. To afford an accurate indication of the setting of the screw 300, an index finger 304 (Fig. 1) is pivoted at 306 (Fig. 10) to a lug 308 formed on the slide 224 and extends rearwardly over a graduated scale 310 (Fig. 1) also secured to the slide 224. The finger 304 has on its upper side (Fig. 11) a lug 312 which lies between the flanges 296 and causes the finger 304 to be swung over the scale as the pin 232 is moved longitudinally by operation of the screw 300.

In the use of the apparatus, an outsole having activated cement on its upper marginal surface 45 and a hole punched centrally of its rear portion is placed upon the pad cover 30. The operator then grasps the handle 240 and moves the slide 224 back or forward to engage the pin 236 with the hole in the rear end of the sole, the sole being moved laterally if necessary to effect this. Upon release of the handle 240 the pawls 270, 272 engage the teeth 276 and prevent rearward movement of the slide. Now if the slide 34 is not aligned with the longitudinal median line of the forepart of the sole, the screw 48 will be loosened and the member 40 carrying the slide will be swung to one side or the other to effect such alignment, the range of movement of the member 40 being sufficient so that the direction of movement of the slide 34 may be aligned with the median line of either a right or a left shoe. Assuming that a right outsole O is being located, the parts will be positioned as shown in Fig. 1. In this case the ball line sole gage 154 is adjusted farther rearwardly of the sole than the ball line gage 152 by use of the screw-and-slot adjustment 158. Of course, for a left sole the positions of the ball line gages would be reversed. The operator now, by depressing a treadle to operate the angle lever 106 as disclosed in the patent above referred to, releases the spring 108 which acts to tip the rocker 92 clockwise, thus moving the slide 34 toward the shoe until the sole V-gage 24, 26 engages the toe end of the sole. Upon contact of the gages 24, 26 with

opposite sides of the sole, the spring 58 is compressed and the lever 52 rocked forwardly about its pivot 36 to cause the cam 54 to bind against the plate 56, thus locking the sole gage from movement away from the sole. While the V-gage is moved toward the sole the slides 180 are being moved rearwardly of the pad, the lugs 178 first traveling in the straight portions 171 of the slots 170 and, after the sole V-gage has engaged the sole, the lugs 178 operate in the inclined slots 170 to move the sole gages 152, 154 into contact with the sole. Should one of the ball gages engage the sole before the other, the spring 192 associated with that gage will yield to permit the other gage to come into contact with the sole. When both gages 152, 154 have found the sole, they are, of course, positively locked against outward movement by the lugs 178 in the inclined slots 170. In case a small sole is being located and the V-gage 24, 26 is initially so far from the sole that the ball gages reach the sole before the toe gages, the initial position of the slide 34 may be changed by adjusting the stop screw 84 to vary the initial position of the V-gage longitudinally of the sole.

A shoe having cement on the overlasted portion of its upper is now seated at its rear end in the V-gage 248 and the shoe and V-gage moved rearwardly against the tension of the spring 260 until the toe of the shoe will enter the shoe V-gage 112. The surfaces 113 of the V-gage 112 have sufficient heightwise extent parallel to the edge faces of the sole gage 24, 26 so that the shoe may be located by them while the forepart is out of contact with the sole located by the sole V-gage 24, 26, the shoe being held suspended over the sole by pressure of the gage 248 toward the gage 112. This relation of the shoe and sole is shown somewhat diagrammatically in Fig. 12.

Now, to insure that the shank portion of the sole will be laid against the shank portion of a shoe without putting the shank portion of the sole under such longitudinal stress that it will tend to separate from the shoe, the shank portion of the outsole is made to bulge toward the shank portion of the shoe located above it by pushing the slide 224 toward the shoe to cause the pawls 270, 272 to move a few notches, this movement of the slide being permitted by a slight further compression of the spring 260. The outsole O will be now in the condition illustrated in Fig. 12, the upward bulge of the outsole furnishing sufficient material to be laid against the shank portion of the shoe as the shoe and sole are brought together by downward pressure of abutments 314, 316 with which the machine is provided. As the shoe moves downwardly, the toe thereof is guided by the surfaces 113 into proper relation to the sole positioned against the edge faces of the plates 24, 26 and the ball portion of the shoe is guided by the shoe gages 194, 198 into proper relation to the sole at the ball. At the heel end of the shoe the gage 248 moves downwardly about its pivot 256 until the shoe S and sole O assume the position shown in dotted lines in Fig. 9. If, as sometimes happens, the shank portion of the outsole O is distorted so that its rear portion is too far to one side or the other, the slide 224 carrying the gages for the rear end of the sole and shoe may be moved with the slide 204 to one side or the other against one or the other of the springs 210 to aline the shoe gage 248 with the position of the shoe as determined by the toe V-gage 112 and the ball line gages 194, 198, the pin

236 engaging the hole in the rear end of the sole causing the relation of the rear end of the sole to the rear end of the shoe to be corrected as the slides 204, 224 are moved laterally. If, because of the unsymmetrical shape of the rear end of the last, it is necessary to position the pin 236 out of central position with respect to the surfaces of the V-gage 248 which engage the shoe, the screw 302 will be turned in the proper direction to bring the rear end of the sole and the rear end of the shoe in the proper relation, the amount and direction of this adjustment being indicated by the finger 304 on the scale 310.

Having thus described my invention, what I claim as new and desire to secure by Letters Patent of the United States is:

1. A pad box for use in applying pressure to shoe bottoms provided with a sole-receiving pad, and a gage for locating the end of a sole comprising pairs of plates pivoted at one edge, the plates of each pair being adapted to rest at their free edges upon the pad.

2. A pad box for use in applying pressure to shoe bottoms provided with a sole-receiving pad, and a gage movable into and out of operative position for locating one end of a sole on the pad, said gage comprising a plurality of pairs of flat members arranged for pivotal movement independently of each other, the free edges of each pair being straight, in alinement, and the pivot of one pair being at an angle to that of the other pair, said members, when in operative position, being adapted to rest at their free ends upon the sole-receiving surface of the pad.

3. A pad box for use in applying pressure to shoe bottoms provided with a sole-receiving pad, and a gage for positioning one end of a sole on the pad, said gage comprising pairs of oppositely disposed plates pivotally mounted at one edge and arranged to rest by gravity on the pad at their opposite edges, said plates being also arranged for movement longitudinally of the pad.

4. A pad box for use in applying pressure to shoe bottoms provided with a sole-receiving pad, and a gage for positioning a sole on the pad, said gage comprising a plurality of oppositely disposed sets of plates mounted for pivotal movement independently of each other and arranged to rest by gravity on the pad at their free edges, the free edges of each set of plates being adapted to engage the edge face of the sole and being located substantially at right angles to the free edges of the opposite set of plates.

5. A pad box for use in applying pressure to shoe bottoms provided with a sole-receiving pad, a slide mounted for movement longitudinally of a shoe on the pad and for movement in a vertical plane about a pivot, the front end of the slide having a lug engaging the pad to limit its movement toward the pad, and a V-gage mounted on the slide and consisting of plates pivotally mounted at one edge, the free edges of the plates engaging the pad by gravity and being arranged at approximately a right angle to serve as a V-gage for locating a sole.

6. A pad box for use in applying pressure to shoe bottoms provided with a sole-receiving pad, a slide mounted for movement longitudinally of a shoe on the pad and for movement in a vertical plane about a pivot, means for limiting movement of the front end of the slide toward the pad, and a gage mounted on the slide and consisting of plates pivotally mounted at one edge, the free edges engaging the pad by gravity and being ar-

ranged at approximately a right angle to each other to serve as a V-gage for locating the sole.

7. A pad box for use in applying pressure to shoe bottoms provided with a sole-receiving pad, a V-gage for locating the toe end of a sole, a V-gage for locating the toe end of a shoe, means for relatively adjusting said gages longitudinally of the forepart of the shoe, and a graduated scale and index finger to indicate the amount of said relative adjustment.

8. A pad box for use in applying pressure to shoe bottoms provided with a sole-receiving pad, a first slide arranged for movement longitudinally of the pad, a gage on said slide, a second slide on the first slide, a V-gage on the second slide for engaging the shoe, means for effecting a fine adjustment of one slide relatively to the other to set the gages, and an indicator actuated by relative movement of the slides to magnify such movement.

9. A pad box for use in applying pressure to shoe bottoms provided with a sole-receiving pad, a slide arranged for movement longitudinally of the pad, a gage on said slide, a second slide mounted on the first-named slide, a gage on said second slide, means for effecting relative longitudinal movement of said slides, and means for measuring said relative movement comprising a graduated plate, an index finger pivoted on said plate and connections between the finger and said slides whereby said finger is caused to indicate said relative movement on the graduated plate.

10. A pad box for use in applying pressure to shoe bottoms provided with a sole-receiving pad, a first slide arranged for movement longitudinally of the pad, a sole gage on said slide, a second slide on the first slide, a V-gage on the second slide for engaging a shoe, a graduated plate carried by the first slide, an index finger pivoted to the plate, an arm connected by the same pivot to the plate, connections between the finger and the arm permitting relative adjustment of them about their common pivot, means connecting the second slide to the arm, and means for relatively moving the slides.

11. A pad box for use in applying pressure to shoe bottoms provided with a sole-receiving pad, a slide mounted for movement longitudinally of a shoe on the pad and for movement in a vertical plane about a pivot, means for limiting movement of the front end of the slide toward the pad, a sole V-gage mounted on the slide, and a shoe V-gage located above the sole V-gage and mounted on said slide for both lateral and longitudinal adjustments relatively to the sole gage.

12. A pad box for use in applying pressure to shoe bottoms provided with a sole-receiving pad, means for locating the toe end of a sole, a pair of arms movable about axes perpendicular to the pad, feelers on said arms arranged to engage the sole one at each end of the ball line, yielding means through which the feelers are operated to engage the sole, and means for positively preventing reverse movement of the feelers.

13. A pad box for use in applying pressure to shoe bottoms provided with a sole-receiving pad, a pair of arms movable about axes perpendicular to the pad, ball line gages on said arms, slides guided for movement parallel to each other lengthwise of the box, slotted plates carried by the arms, and lugs on the slides engaging inclined slots in the plates to move the arms to-

ward each other and prevent separation of the arms.

14. A pad box for use in applying pressure to shoe bottoms provided with a sole-receiving pad, a slide movable longitudinally of the pad, a V-gage on the slide to locate the end of the sole, ball line gages arranged for movement toward the sole at the opposite ends of the ball line, means for first advancing the slide to cause the V-gage to engage the end of the sole and for then advancing the ball line gages yieldingly to find the sole, and means acting on contact with the sole for locking each of said gages.

15. A pad box for use in applying pressure to shoe bottoms provided with a sole-receiving pad, a pair of ball line gages arranged relatively to locate a shoe and sole at the ends of the ball line, means for advancing each ball line gage toward its end of the ball line comprising a plate having a slot, a slide movable longitudinally of the pad and having a stud engaging said slot, the inclination of the slot being such that the gages are positively locked in operative position against movement away from the shoe, and means for yieldingly moving the slide.

16. A pad box for use in applying pressure to shoe bottoms provided with a sole-receiving pad, a slide mounted for movement longitudinally of the pad in a guideway, a V-gage mounted on the slide to locate the end of a sole, a lever on the slide having a cam adapted to lock the slide to the guideway against movement away from the sole, a spring initially holding the cam out of action, and means connected with the lever for advancing the slide, resistance to movement of the slide by contact of the gage with the sole causing the spring to be overcome and the slide to be locked by the cam.

17. A pad box for use in applying pressure to shoe bottoms provided with a sole-receiving pad, a slide mounted for movement longitudinally of the pad, a sole gage for engaging the toe end of a sole, and means for adjusting said gage laterally of the sole about an arc adapted to position them at the proper angle for operating upon shoes and soles having different toe swings.

18. A pad box for use in applying pressure to shoe bottoms provided with a sole-receiving pad, a pair of ball line gages arranged relatively to locate a shoe and sole at the ends of the ball line, and shoe and sole gages for engaging respectively the shoe and sole at the toe end, said gages being arranged for bodily movement laterally of a shoe on the pad to position them properly for locating right and left shoes and soles.

19. A pad box for use in applying pressure to shoe bottoms provided with a sole-receiving pad, a pair of ball line gages arranged relatively to locate a shoe and sole at the ends of the ball line, and shoe and sole V-gages engaging respectively the shoe and the sole at the toe end, said gages being mounted for adjustment to maintain a line bisecting the angle of the V-gages substantially coincident with the longitudinal median line of the forepart of shoes and soles having different swings.

20. A pad box for use in applying pressure to shoe bottoms provided with a sole-receiving pad, a pair of ball line shoe and sole gages arranged to locate a sole and shoe relatively to each other at the ends of the ball line, and shoe and sole V-gages engaging respectively the shoe and the sole at their toe ends, said V-gages being arranged for bodily movement relatively to the ball line gages about a center located approxi-

mately at the intersection of the longitudinal median line of the forepart of the shoe with the longitudinal median line of the rear part.

21. A pad box for use in applying pressure to shoe bottoms provided with a sole-receiving pad, means for locating the toe end of a sole, means for locating the toe end of a shoe, means for relatively adjusting said locating means longitudinally of the forepart of the shoe, and means constructed and arranged for bodily movement of said shoe and sole locating means along an arc struck from a point approximately at the intersection of the longitudinal median line of the forepart with the longitudinal median line of the rear part of a shoe placed on the pad.

22. A pad box for use in applying pressure to shoe bottoms provided with a sole-receiving pad, a pair of ball line gages arranged relatively to locate the sole at the ends of the ball line, and shoe and sole gages engaging respectively the shoe and sole at their toe ends, said last-named gages being arranged for bodily movement relatively to the ball line gages about a center located approximately at the intersection of the longitudinal median line of the forepart of the shoe with the longitudinal median line of the rear part.

23. A pad box for use in applying pressure to shoe bottoms provided with a sole-receiving pad, a V-gage for locating the toe end of a sole, and a V-gage for locating the toe end of a shoe, said V-gages being arranged for bodily movement along an arc struck from a point approximately at the intersection of the longitudinal median line of the forepart with the longitudinal median line of the rear part of a shoe placed on the pad.

24. A pad box for use in applying pressure to shoe bottoms provided with a sole-receiving pad, and means for locating the toe of a sole and the toe of a shoe, said means being arranged for bodily movement along an arc struck from a point approximately at the intersection of the longitudinal median line of the forepart with the longitudinal median line of the rear of a shoe placed on the pad.

25. A pad box for use in applying pressure to shoe bottoms provided with a sole-receiving pad, a slide movable transversely of the box, a slide arranged for movement longitudinally of the box, shoe and sole gages carried by said last-named slide, and spring means acting to maintain the transversely movable slide in central position relatively to the pad box.

26. A pad box for use in applying pressure to shoe bottoms provided with a sole-receiving pad, a slide movable transversely of the box, a slide arranged for movement longitudinally of the box, shoe and sole gages carried by the last-named slide, means for holding the transverse slide yielding in central position relatively to the pad box, and means for adjusting the shoe and sole gages transversely of the pad relatively to each other.

27. A pad box for use in applying pressure to shoe bottoms provided with a sole-receiving pad, a longitudinally movable slide, a V-gage mounted thereon for movement longitudinally of the shoe relatively to the slide, a spring urging the V-gage toward a shoe on the pad, a sole gage for locating a sole relatively to a shoe in the V-gage, means for holding the slide from movement away from the shoe on the pad, and means for effecting relative lateral adjustment of the sole gage and V-gage.

28. A pad box for use in applying pressure to shoe bottoms provided with a sole-receiving pad,

a slide movable transversely of the box, a slide arranged for movement longitudinally of the box, a V-gage for the shoe carried by the longitudinally movable slide, a sole gage comprising a tongue and pin also carried by said slide, means for relatively adjusting the V-gage and the tongue transversely of the pad, and an indicator to show the amount of said transverse relative adjustment.

29. A pad box for use in applying pressure to shoe bottoms provided with a sole-receiving pad, a slide movable transversely of the box, a slide arranged for movement longitudinally of the box on the transverse slide, a shoe gage arranged for movement longitudinally of the longitudinally movable slide, a sole gage carried by the longitudinally movable slide, and means for relatively adjusting the sole gage and shoe gage transversely of the pad.

30. A pad box for use in applying pressure to shoe bottoms provided with a sole-receiving pad a longitudinally movable slide, a V-gage mounted therein for movement longitudinally of the pad, a spring urging the V-gage toward a shoe on the pad, a tongue having a pin to engage a hole in the rear end of the sole on the pad, and means for holding the slide from movement away from the shoe on the pad.

31. A pad box for use in applying pressure to shoe bottoms provided with a sole-receiving pad, a slide movable longitudinally of the pad at its rear end, a shoe gage mounted thereon for movement longitudinally of the slide, a spring urging the shoe gage toward a shoe on the pad, a sole gage for the rear end of a sole on the pad, and means for holding the slide from movement away from a shoe on the pad.

32. A pad box for use in applying pressure to shoe bottoms provided with a sole-receiving pad, a pin mounted for endwise movement transversely of the box, a sole gage secured to the pin, and a screw having a collar engaging a groove in the pin for moving the pin endwise.

33. A pad box for use in applying pressure to shoe bottoms provided with a sole-receiving pad, a slide movable transversely of the box, a slide arranged for movement longitudinally of the box, shoe and sole gages carried by the longitudinal slide, and means for holding the transverse slide yielding in central position relatively to the pad box.

34. A pad box for use in applying pressure to shoe bottoms provided with a sole-receiving pad, a slide movable transversely of the box, a slide arranged for movement longitudinally of the box, shoe and sole gages carried by the longitudinal slide, and a pair of springs acting to maintain the transverse slide in central position relatively to the pad box, one only of said springs being tensioned by transverse movement of the slide.

35. A pad box for use in applying pressure to shoe bottoms provided with a sole-receiving pad, a slide movable transversely of the box, a slide arranged for movement longitudinally of the box, a shoe gage carried by the longitudinally movable slide, a sole gage also carried by said slide, means for relatively adjusting the sole gage and the shoe gage transversely of the pad, and an indicator to show the amount of said transverse relative adjustment.

36. A pad box for use in applying pressure to shoe bottoms provided with a sole-receiving pad, a slide movable longitudinally of the pad at its rear end, a shoe gage mounted thereon for movement longitudinally of the pad relatively to

the slide, a spring urging the shoe gage toward a shoe on the pad, a sole gage carried by the slide for engaging the rear end of the sole on the pad, and means for holding the slide from movement away from the shoe on the pad.

37. A pad box for use in applying pressure to shoe bottoms provided with a sole-receiving pad, a longitudinally movable slide, a V-gage mounted thereon for movement longitudinally of the pad, a spring urging the V-gage toward a shoe on the pad, a tongue carried by the longitudinally movable slide having a pin arranged to engage a hole in the rear end of the sole on the pad, means for holding the slide from movement away from the shoe on the pad, and means for effecting relative lateral adjustment of the tongue and V-gage.

38. A pad box for use in applying pressure to shoe bottoms provided with a sole-receiving pad, a slide mounted for movement longitudinally of the pad box at one end thereof, a shoe gage mounted on the slide for movement longitudinally of the pad, a spring urging the shoe gage toward a shoe on the pad, a tongue normally resting on the pad and having a pin for engaging a hole in the rear end of the sole on the pad; means for holding the slide from movement away from the shoe on the pad, means for lifting the tongue to receive the rear end of the sole, and means operated by the tongue-lifting means for releasing the holding means.

39. A pad box for use in applying pressure to shoe bottoms provided with a sole-receiving pad, a slide mounted for movement longitudinally of the pad at one end thereof, a shoe gage mounted thereon for movement longitudinally of the pad, a spring urging said shoe gage toward a shoe on the pad, a sole gage movable to engage a sole and locate the sole relatively to the shoe, means for holding the slide from movement away from the shoe on the pad, means for operating the sole gage to release it from the sole, and means actuated by said operating means for releasing the slide-holding means.

40. A pad box for use in applying pressure to shoe bottoms provided with a sole-receiving pad, a longitudinally movable slide, a V-gage mounted therein, a spring urging the V-gage toward a shoe on the pad, a tongue having a pin to engage a hole in the rear end of the sole on the pad, means for holding the slide from movement away from a shoe on the pad, means for lifting the tongue to receive the rear end of the sole, and means operated by the tongue-lifting means for releasing the holding means.

41. A pad box for use in applying pressure to shoe bottoms provided with a sole-receiving pad, a V-gage to locate the toe end of a sole, a V-gage for locating the toe end of a shoe, said shoe gage having sufficient heightwise extent to insure that the toe of a shoe may be positioned relatively to the sole in the sole gage without contact with the sole, a pin and tongue to engage the heel portion of the sole, a V-gage to receive the rear end of the shoe, and means for resiliently urging the rear shoe gage toward the shoe so that a shoe may be suspended in the toe and rear V-gages in proper relation to a sole located by the sole V-gage at the toe and by the pin at its rear end.

42. A pad box for use in applying pressure to shoe bottoms provided with a sole-receiving pad, a V-gage to locate the toe end of a sole, a shoe gage for locating the toe end of a shoe relatively to the V-gage, the shoe gage having

sufficient heightwise extent to insure that the toe of a shoe may be positioned relatively to the sole in the sole gage without contact with the sole, means to engage the rear portion of the sole, a gage to receive the rear end of the shoe, and means for resiliently urging the rear shoe gage toward the shoe so that the shoe may be suspended in the toe and rear shoe gages in proper relation to the sole located by the sole V-gage at the toe and by the means engaging the rear portion of the sole.

43. A pad box for use in applying pressure to shoe bottoms provided with a sole-receiving pad, a gage to locate the toe end of a sole, a gage to locate the toe end of a shoe, said shoe gage having sufficient extent heightwise of the pad to insure that the toe of a shoe may be positioned relatively to the sole in the sole gage without contact with the sole, a gage for the rear portion of the sole, a gage to receive the rear end of the shoe, and means for resiliently urging the rear shoe gage toward the shoe so that the shoe may be suspended in the toe and shoe gages in proper relation to a sole located by the gage at the toe end and by the sole gage at its rear end.

44. A pad box for use in applying pressure to shoe bottoms provided with a sole-receiving pad, means for locating relatively the forepart of a shoe and sole, means for locating the rear part of a sole, means for yieldingly urging the rear shoe-locating means forwardly to hold the shoe against the forepart-locating means, and means permitting advance of the means for locating the rear end of the sole toward the toe of the shoe to hump the shank portion of the sole toward the shank of the shoe.

45. A pad box for use in applying pressure to shoe bottoms provided with a sole-receiving pad, means for locating relatively the forepart of a shoe and sole, means for locating the rear part of a sole, means for locating the rear part of a shoe, means for yieldingly urging the rear shoe-locating means toward the forepart-locating means, a slide movable longitudinally of the pad and carrying said means for locating the rear end of the sole, and a ratchet and pawl for holding said slide against movement rearwardly of the shoe whereby the slide may be pushed forwardly relatively to the rear shoe gage to cause the shank portion of the sole to assume a longitudinal curvature.

46. A pad box for use in applying pressure to shoe bottoms provided with a sole-receiving pad, means for engaging each end of a sole to locate the sole relatively to the pad, gages arranged to find the sole by engagement with the sole at each end of the ball line, means for holding the gages against movement away from the sole, means for locating a shoe with respect to the sole so located, and a gage for the rear end of the shoe, the rear shoe and sole gages being mounted for limited lateral movement together to align the rear end of the sole with the shoe and to bring the rear shoe gage into proper lateral relation to the position of the shoe as determined by the forepart gages.

47. A pad box for use in applying pressure to shoe bottoms provided with a sole-receiving pad, means for locating a sole on the pad, a shoe toe gage having angularly related plane surfaces substantially perpendicular to the pad and extending a substantial distance heightwise thereof, a gage for the rear end of the shoe

having angularly related surfaces embracing the shoe and being mounted for movement toward the pad, and resilient means urging the shoe toe gage and shoe rear end gage toward each other so that a shoe caused to engage at its ends said angularly related surfaces will be sustained out of contact with the located sole and may be brought into contact with the sole by pressure applied heightwise of the shoe.

48. A pad box for use in applying pressure to shoe bottoms provided with a sole-receiving pad, a V-gage for locating the toe end of a sole and a V-gage for locating the toe end of a shoe, said shoe gage having heightwise extent perpendicular to the face of the pad to insure that the shoe may be located relatively to the sole without contact therewith, shoe and sole gages for engaging the shoe and sole at the ends of the ball line, means for locking the ball line gages against separation, a gage for the rear end of the sole, and a gage for the rear end of the shoe, said shoe gage being arranged for limited movement toward the pad, the shoe gages at the toe and heel being adapted to sustain and locate a shoe with respect to a sole located by the sole

10 gages with the shoe bottom out of contact with the sole.

49. A pad box for use in applying pressure to shoe bottoms provided with a sole-receiving pad, a gage to locate the toe end of a sole, a gage for locating the toe end of a shoe relatively to the sole, the shoe gage having sufficient heightwise extent to insure that the toe of the shoe may be positioned relatively to the sole without contact therewith, a gage for the rear portion of the sole, sole and shoe gages for relatively locating the sole and shoe at the ends of the ball line, means for locking said gages to hold the shoe and sole in position, a gage to receive the rear end of the shoe, means for resiliently urging the rear shoe gage toward the shoe so that the shoe may be suspended by pressure of the rear shoe gage toward the toe shoe gage in proper relation to the sole located in the sole gages, and means permitting limited lateral movement of the rear shoe gage and the rear sole gage to align them with the forepart of the shoe held in place by the forepart shoe gages.
